RELAY SYSTEM AND METHOD

Application filed September 12, 1928. Serial No. 305,470.

This invention relates generally to relay systems and methods of operating the same for repeating and amplifying current variations. It is particularly applicable for repeating and amplifying currents of radio frequency employed in signalling systems.

It is an object of this invention to devise a novel form of relay system and method whereby positive feed back coupling between the output and input circuits can be balanced out to prevent generation of local oscillations.

It is a further object of this invention to devise a novel form of neutralizing system for use with electron relay amplifiers, which is characterized by the fact that the reactive output circuit of the relay is completed by a connection to the relay input circuit.

It is a further object of this invention to devise a neutralizing system for electron relays characterized by operation of the cathode of the relay at a potential differing from ground potential.

Further objects of the invention will appear from the following description in which I have set forth the preferred embodiment of my invention. It is to be understood that the appended claim is to be accorded a range of equivalents consistent with the state of the prior art.

Referring to the drawings:

Fig. 1 is a simplified circuit diagram illustrating certain principles of my invention.

Fig. 2 is a circuit diagram illustrating my invention applied to the electron relay amplifier of a system.

When using electron relays for amplifying current variation, it is generally desirable to provide means for preventing generation of local oscillations due to positive feed back coupling between the output and input circuits. My invention makes possible this result in a novel and simplified way, and without the use of additional reactances other than those ordinarily employed in the input and output circuits.

The principles of my invention can best be explained by reference to Fig. 1, in which I have shown an electron relay consisting of the usual grid or control element 11, plate or

anode 12, and cathode 13. The input circuit is formed by inductance 14, having one point thereof connected to grid 11, and another point connected to cathode 13. The output or plate circuit includes inductance 16 having one point thereof connected to plate 12. Conductor 17 which is generally employed for completing the output circuit, has been shown connected to a tap 18 on inductance 14, rather than directly to cathode 13. For convenience I have indicated a measuring device 19 inserted in series with conductor 17.

Ordinarily with a circuit arrangement such as described above, the electron relay because of its construction provides capacitances between its elements which can be represented by condensers 1, 2 and 3. One or more of these capacitances ordinarily serve to reactively couple the output to the input so that positive feed back of energy is provided. Thus because of such positive feed back the ordinary amplifier relay system tends to oscillate locally, particularly if the input and output circuits are tuned to the same radio frequency.

Assuming that oscillations can be induced in the output circuit of the relay, as for example, by an oscillator circuit 21 inductively related to inductance 16, energy introduced thru conductor 17 tends to divide into two reactive paths provided by inductance and completed thru the inter-electrode capacitance of the relay. By adjusting the position of tap 18, it is possible to balance the two reactive paths so that no corresponding potential differences occur between the grid 11 and cathode 13. In other words the relay and associated circuits can be caused to form a bridge circuit in which grid 11 and cathode 13 are at points neutral with respect to each other. When the proper position for tap 18 has been found, oscillation set up to the input circuit of the relay, as by means of an exciting circuit 22, will cause no corresponding current flow to occur thru conductor 17.

One manner in which the principles outlined above can be used in practice is shown in Fig. 2. In this case both inductances 14 and 16 are tuned by means of condensers 23 and 24. A blocking condenser 26 is employed

in series with the plate circuit, and an operating anode potential is maintained upon the plate from a suitable source of current represented by "B" battery 27, the negative terminal of this battery being shown connected to ground 28, while the positive terminal is connected to the plate thru a suitable high frequency choke 29. Means is also shown for maintaining a negative bias upon the grid of 10 the relay, and which in this case utilizes grid condenser 31 and grid leak resistance 32 connected to the ground in series with high frequency choke 33. The cathode for the relay is of the usual filament type, excited from a 15 suitable source of current represented by the step-down alternating current transformer 34. The output terminals of this transformer are connected to the terminals of the filament thru high frequency chokes 36, in order to 20 permit the cathode to operate at a potential differing from ground potential. The lead 37 for completing the grid circuit of the relay is connected to the mid point of an impedance placed across the terminals of the 25 cathode. Such an impedance can be formed by a pair of condensers 38. As in the case of Fig. 1, the tuned plate circuit is completed thru lead 17 connected to tap 18 upon inductance 16. The input circuit is supplied with 30 high frequency oscillations from a suitable source represented by circuit 39, while the output circuit supplies a load represented by 35 the radio antenna circuit 41.

In operating the system of Fig. 2, the position of tap 18 is adjusted until the relay repeats and amplifies the high frequency oscillations without continuing in oscillatory condition after excitation of the grid circuit has ceased. When so adjusted positive coupling 40 from the output to the input of the relay which would ordinarily cause corresponding potential differences between the grid and the cathode, no longer causes such variation and therefore cannot cause generation of local 45 oscillations. The cathode 13 operates at potentials differing from ground potential. When amplifying high frequency oscillations an appreciable current flow occurs through lead 17.

50 I claim:

In a translating system, an input circuit, an output circuit, and a translating device having an input electrode, an output electrode and a common input and output electrode, 55 said input circuit comprising at least one impedance element connected between said input electrode and said common electrode, and said output circuit being connected between said output electrode and a tap on said input circuit at such a point that the ratio of the impedance of that portion of the input circuit between said tap and said common electrode, to the impedance of the path between said tap and said input electrode is substantially 60 the same as the ratio between the inherent

capacity paths between said common and output electrodes and between said input and output electrodes.

In testimony whereof, I have hereunto set my hand.

FREDERICK A. KOLSTER.
